UNITED STATES PATENT OFFICE

LESLIE T. CARPENTER, OF LYNWOOD, CALIFORNIA

WRENCH

Application filed February 14, 1931. Serial No. 515,844.

My invention relates generally to wrenches and more particularly to wrenches of the character adapted for the gripping and turning of articles presenting relatively smooth and curved surfaces such as pipes for example.

It is a purpose of my invention to provide a wrench of the above described character, which is of simple and rugged construction, 10 and embodies a flexible linked member preferably in the form of a chain capable of being readily applied to an article in embracing relation thereto and correlated with extremely simple means by which the chain is caused 15 to positively and uniformly grip an article for turning by the wrench with ease and dispatch.

I will describe only one form of wrench embodying my invention, and will then point 20 out the novel features thereof in claims.

In the accompanying drawings:

Figure 1 is a view showing in front elevation, partly broken away, one form of wrench embodying my invention.

Figure 2 is a view of the wrench in side elevation, and

Figure 3 is a vertical sectional view taken on the line 3—3 of Figure 1 and looking in the direction of the arrows.

Referring specifically to the drawings in which similar reference characters designate similar parts in each of the several views, my invention in its present embodiment comprises a handle H in the form of a rectangular bar 10 of suitable length to obtain the necessary leverage, having at one end thereof plates 11 and 12 which are secured on opposite sides of the bar by rivets 13 extending through registering openings in the bar and plates. That end of the bar to which the plates are secured co-acts with the plates to form a head K having a series of teeth thereon with which links of a chain C constituting a flexible gripping member, are adapted to 40 intermesh.

One end of the chain C is pivotally connected at 15 to a pair of links 16 and 17 pivotally connected to the handle H by a pin 18 extending through registering openings in 45 the pair of links, plates 11 and 12 and the

bar 10 as shown in Figure 3. In the present instance both the bar and plates are provided with the teeth above referred to, the bar having three teeth indicated at 19, radially arranged concentric with respect to the axis of 55 the pin 18 and equally spaced circumferentially. The plates 11 and 12 are each provided with two radially arranged teeth 20 disposed in alinement with each other and staggered circumferentially with respect to 60 the teeth 19 for co-action therewith in providing a segmental gear having a pitch equal to that of the links of the chain, with alternate teeth offset laterally from each other to intermesh with the chain links as shown in Figure 65 1.

To the endmost link of the chain at the free end of the latter is pivotally connected a relatively long link 21 which constitutes a pilot link and facilitates insertion of the 70 chain through the opening between the pair of links 16 and 17 after the chain has been placed around an article to be gripped. The links of the chain C are provided along one longitudinal edge with transverse teeth 22 75 for the purpose of insuring a firmer grip of the chain upon an article, whereas the opposite side edges of the chain links are smooth for gripping an article without marring the 80 latter.

In the use of the wrench the chain is first extended around the article to be gripped and turned, and the free end of the chain is inserted through the opening between the links 16 and 17. The chain is then drawn taut 85 about the article and the chain links are intermeshed with the teeth 19 and 20 as shown in Figure 1, after which the handle H is rocked about the axis of the pin 18 in the direction of the arrow. This operation causes the teeth to co-act with the chain links in tightening the chain about the article so as to firmly and uniformly grip the latter. It will be clear that continued force exerted 90 upon the handle in the direction of the arrow will tend to further tighten the chain and turn the article. Either the smooth or toothed sides of the chain links can be presented to the article by reversing the position 95 100

of the chain and links 16 and 17 with respect to the article.

A ratchet feeding effect of the chain upon the article can be obtained for use in restricted location by simply holding the free end of the chain taut and rocking the handle back and forth so that in one direction the chain will loosen its grip upon the article and slip freely around the latter. It will be manifest that the construction of the wrench permits its use in restricted spaces as only sufficient clearance need exist between an obstruction and the article to be gripped, for the passage of the chain.

Although I have herein shown and described only one form of wrench embodying my invention, it is to be understood that various changes and modifications may be made therein without departing from the spirit of the invention and the spirit and scope of the appended claims.

I claim:

1. A wrench comprising a handle, a flexible chain having central links and side links pivotally connecting adjacent central links on opposite sides thereof, means for pivotally connecting one end of the chain to the handle to permit looping of the chain about an article to be gripped, and a series of circumferentially spaced alternating central and side teeth on the handle radially disposed and concentrically arranged with respect to said pivotal connection, the side teeth being arranged in pairs aligned transversely of the series and offset laterally relative to the central teeth for intermeshing with both the central and side chain links to effect uniform tightening of the chain around the article in response to rocking of the handle in one direction about the axis of said pivotal connection.

2. A wrench comprising a handle bar, a pair of plates secured to the bar at one end thereof and on opposite sides of the bar, a length of flexible chain having central links and side links pivotally connecting adjacent central links on opposite sides thereof, a pair of links connected to one end of the chain, a pin extending through the bar, plates, and links to pivotally connect the latter and provide space between the links for the insertion of the free end of the chain, a plurality of teeth on said end of the bar, concentrically arranged with respect to the axis of said pin, and other aligned teeth on said plates concentric with respect to the axis of the pin and staggered circumferentially relative to the first teeth for co-action therewith in intermeshing with both the central and side chain links to effect a uniform tightening of the chain around an article in response to rocking of the handle bar in one direction about the axis of said pin.

3. A wrench comprising a handle, a chain having central links and side links pivotally

connecting adjacent central links on opposite sides thereof, the chain being connected to the handle and adapted to form a loop about an article to be gripped, the handle having a series of circumferentially spaced and alternating central and side teeth, the latter being arranged in pairs aligned transversely of the series and offset laterally relative to the central teeth for co-action therewith in intermeshing with the central and side chain links, to tighten the chain about the article in response to movement of the handle in one direction.
